(57) **CLAIM**

The ornamental design for a table leg, as shown and described.

DESCRIPTION

FIG. 1 is a front, right and top perspective view of a table leg, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the table leg that form no part of the claimed design.
